UNITED STATES PATENT OFFICE.

GEORGES E. HENRY, OF MANSFIELD, OHIO, ASSIGNOR TO THE OHIO BRASS COMPANY,
OF MANSFIELD, OHIO, A CORPORATION OF NEW JERSEY.

WINDING MECHANISM.

1,413,582.

Specification of Letters Patent. Patented Apr. 25, 1922.

Application filed November 12, 1920. Serial No. 423,700.

To all whom it may concern:

Be it known that I, GEORGES E. HENRY, a citizen of Switzerland, residing at Mansfield, in the county of Richland and State 5 of Ohio, have invented certain new and useful Improvements in Winding Mechanisms, of which the following is a specification.

My invention relates to a winding or rewinding device and has particular application 10 to spring motors and the like and especially to that particular class of apparatus known as trolley retrievers and trolley catchers and in combination with which I have shown and described my particular 15 device.

The advantages of my device are that it can be thrown into and out of engagement 20 with the spring motor, trolley catcher or trolley retriever at will and its operation is confined to a reciprocating motion in place of a continuous rotary motion and it is simple in construction and involves 25 few parts.

To the attainment of these ends and the 30 accomplishment of other new and useful objects, the invention consists in the novel features of construction, combination and relation of the various parts to be herein-after more fully described and claimed, and shown in the accompanying drawings and 35 in which:—

Fig. 1 is a side view in section of my device attached to a spring motor for controlling a trolley pole rope and with the 40 handle in a lowered or inoperative position and the device out of engagement with the mechanism of the spring motor.

Fig. 2 is a side view in section as in Fig. 1 but the handle in operative position and 45 the device in engagement with the spring motor parts.

Fig. 3 is a view on line 3—3 of Fig. 1.

Fig. 4 is a view on line 4—4 of Fig. 2.

Fig. 5 is an expanded view of those parts 50 of my device contained within the case and difficult to show clearly in other views. This figure also shows the relation of the parts when in operative and inoperative position.

In describing the preferred form of my 55 invention, I will, for simplicity, show it as attached to a trolley rope tender for merely controlling the slack in a trolley rope by means of a drum and spring. Numeral 1

is represented by 2 which is secured to 1 by any convenient well known means (not shown). A shaft 3 is shown as secured to the case 1 at the back end and the front end is enlarged to form a hub to better support 60 the cover 2. A reel 5 is mounted on the shaft and has a projection 6 to which is secured one end of a spring 7 at the points 8. The other end of the spring is secured to the case at 9. A trolley rope 10 is secured to the reel and the other end of the rope to a trolley pole. To the front face of the reel is secured a ratchet wheel 11 having teeth 12 as better shown in Fig. 5. To the inner face of the cover is a circular 70 boss 13 and mounted on the boss is a reciprocating plate 14, (Fig. 3 and Fig. 5^x) which has a projecting clevis 15 which projects through a slot 16 in the cover. The plate 14 is permitted to rotate back and 75 forth through the angle formed by the lines AC—BC, or in other words is limited only by the extent of opening of the slot 16. To the projecting clevis 15 is pivoted a handle 17 at the point 18 and in such manner that 80 it can be raised or lowered, as shown by Figs. 1 and 2, about the pivotal point 18 and when in a closed or inoperative position as in Fig. 1 it is held in that position by the spring latch 19 engaging the handle through 85 the opening 20. Any convenient and obvious means may be used to maintain the handle as in Fig. 1 as I am not claiming any specific means. At the pivotal end of the handle is a lug 21 adapted to engage 90 a shifting plate 22 (See Fig. 5^y) and raise it when the handle is lowered or to disengage the plate 14 when the handle is raised and permit the plate 22 to lower.

Secured to the reciprocating plate 14 is a 95 pawl 23 constantly urged backward by a spring 24. This pawl has a projecting stud 25 which projects through a slot 26 in the reciprocating plate without engaging with the plate and also projects through a slot 27 100 in the shifting plate 22 and engages the lower end of the slot 27 and held there by the spring 24. This engagement of the pawl 23 and plate 22 tends to raise and lower the free end of the pawl about the point 28 as a 105 pivotal point, thereby throwing the pawl into or out of coating engagement with the teeth 12 of the ratchet wheel 11. In Figs. 5^y and 1 and 3 the pawl 23 is out of engagement with the ratchet and in Figs. 5^z and 2 110

and 4 the pawl is in engagement with the ratchet wheel. As the reciprocating plate 14 is moved back and forth the pawl moves back and forth with it due to its being pivoted to the plate at the point 28 and since the pawl is yieldingly held in coacting engagement with the ratchet wheel it will tend to engage and re-engage the ratchet wheel when the plate 14 is moved forward and back through the medium of the handle 17. The relative position of the reciprocating and shifting plates and pawl and ratchet wheel is better shown by Fig. 5, Y and Z, when the parts are in operative position to 10 wind or rewind the spring 7.

Pivoted to the cover at the point 29 is a pawl 30 which is constantly held in yielding engagement with a member 31 of the shifting plate 22 by the spring 32. When 20 the handle is raised and the shifting plate allowed to drop the pawl 30 engages with the ratchet wheel 11 and prevents the rotation of the ratchet wheel and reel in the direction D of the arrow so that whenever the handle is moved so as to move the ratchet wheel in the direction E of the arrow, the pawl 30 will maintain the ratchet wheel against rotation of the wheel in the reverse or D direction by the spring 7. The pawl 30 might be termed the rotating pawl and the pawl 30 the holding pawl.

The shifting plate 22 is held in position by the slot 33, the sides of which engage the boss 13 on the cover but permit an upward 35 and downward movement. The plate 22 is further held in place by the channel 34 in the rear face of the plate 14.

The operation of the device above described and shown by the drawings is as follows:—Upon raising the handle 17 the shifting plate 22 is free to drop through the action of gravity and springs 24 and 32. This permits pawls 23 and 30 to engage the ratchet wheel 11. The handle is now reciprocated which imparts a forward and backward movement to the pawl 23 and as the handle is moved forward the ratchet wheel is rotated in the direction E of the arrow and an amount proportional to the forward 45 movement of the handle, and this movement is further imparted to the reel and spring 7 to wind the same. Upon moving the handle in the backward direction the pawl 23 is permitted to ratchet over the teeth 12 by 50 the spring 24 and the pawl 30, engaging the ratchet wheel prevents the wheel moving backward with the backward movement of the pawl 23, under a force exerted by the spring 7. This backward and forward motion of the handle is continued until the 55 spring 7 has been wound to the desired amount. One end of the rope is then secured to the reel and the other end to the trolley pole or other device or to the reel only as 60 desired. Upon returning the handle to its

normal or inoperative position the shifting plate 22 is moved upward by the engagement of the projection 21 with the shifting plate 22 and this moves the two pawls out of engagement with the ratchet wheel, thereby 70 allowing the reel to properly function under action of the spring 7 upon the rope.

I have shown my winding, rewinding or tensioning device as attached to the simplest form of spring motor, merely a spring secured to a reel for taking slack out of a trolley rope, to avoid complicating drawings, but it is equally adapted to be associated with other forms of spring motor such as trolley retrievers, motor starters, 80 fishing reels, etc., where it is desired to alter the tension of the spring. My device is also adapted to be used as a winding mechanism, without any reference to a spring; for instance, merely to wind a rope on a reel and 85 it can be put to many uses obvious to one skilled in the art and the device shown and described herein permits of many varieties and I do not wish to be limited in the scope of my invention other than by the appended 90 claims.

Claims:

1. A mechanism comprising a member mounted to impart motion to other mechanism to which it is connected, operating 95 means engaging the member to impart motion thereto, holding means engaging the member to prevent movement of the member in one direction, reciprocating means to be thrown into or out of operating position 100 to impart motion to the operating means and means to move the operating and holding means into or out of engagement with the member simultaneously with the reciprocating means being thrown into or out 105 of operating position.

2. A mechanism comprising a member mounted to impart motion to other mechanism to which it is connected, operating means engaging the member to impart motion thereto, holding means engaging the member to prevent movement of the member in one direction, a handle adapted to be moved into or out of an operating position 110 and means interposed between the operating 115 and holding means and the handle for automatically moving the operating and holding means into or out of engagement with the member.

3. A mechanism comprising a member 120 mounted to impart motion to other mechanism to which it is connected, operating means engaging the member to impart motion thereto, holding means engaging the member to prevent movement of the member 125 in one direction, a handle arranged to impart motion to the operating means and adapted to be moved into or out of an operating position and means permitting a reciprocating motion to the handle. 130

4. A mechanism comprising a member mounted to impart motion to other mechanism to which it is connected, operating means engaging the member to impart motion thereto, holding means engaging the member to prevent movement of the member in one direction, means to impart to the operating means a reciprocating motion, shifting means to move the operating and holding means into or out of engagement with the member, pivotal means secured to the means for moving the operating means and means on the pivotal means for imparting motion to the shifting means. 45
5. A mechanism comprising a member mounted to impart motion to other mechanism to which it is connected, a pivotally mounted member arranged to have a reciprocating motion and having mounted thereon operating means to engage the member and impart motion thereto, holding means pivotally mounted to engage the member to prevent movement in one direction, pivotal means secured to the pivotally mounted member, shifting means to engage the operating and holding means to move them into or out of engagement with the first mentioned member and means on the pivotal means to engage the shifting means and impart motion thereto for the purpose described. 50
6. A mechanism comprising a rotatable wheel mounted to rotate, a pivotally mounted member and pivotally mounted means secured thereto to impart motion to the member, operating means mounted on the member and engaging the wheel, shifting means arranged to move the operating means into or out of engagement with the wheel and means for moving the shifting means. 55
7. A mechanism comprising a rotatable wheel mounted to rotate, a pivotally mounted member and pivotally mounted means secured thereto to impart a reciprocating motion to the member, means to limit the amount of movement of the pivotally mounted member, operating means mounted on the member and engaging the wheel, shifting means arranged to move the operating means into or out of engagement with the wheel and means for moving the shifting means. 60
8. A mechanism comprising a rotatable wheel, operating means to engage the wheel to rotate the same in one direction, holding means to engage the wheel and hold it against rotation in the other direction, shifting means for moving the above means into or out of engagement with the wheel, means for moving the operating means to rotate the wheel, and means compelling the shifting of the operating and holding means into engagement prior to imparting motion to the operating means. 65
9. A mechanism comprising a wheel mounted to rotate and impart motion to a mechanism to which it is secured, a support member, a reciprocating member pivoted on the support, a holding means mounted on the support and adapted to engage and hold the wheel from rotation in one direction, operating means mounted on the reciprocating member and adapted to engage and rotate the wheel, shifting means engaging the holding and operating means to move them into or out of engagement with the wheel and means secured to the reciprocating member to impart motion thereto and compelling the engagement of the holding and operating means with the wheel prior to imparting motion to the reciprocating member. 70
